Patented Feb. 2, 1960

187,166

BOAT TRANSMOM

Donald E. Goodland and Bertil Holm, Traverse City, Mich., assignors to Parsons Corporation, Detroit, Mich., a corporation

Application April 3, 1959, Serial No. 55,332

Term of patent 14 years

(Cl. D71—1)

FIG. 1

FIG. 2

Figure 1 is a perspective view of a boat transom embodying our new design.

Figure 2 is an elevational view thereof.

The broken lines in the drawing are for illustrative purposes only.

We claim:

The ornamental design for a boat transom, substantially as shown and described.

No references cited.
